UNITED STATES PATENT OFFICE.

CHARLES A. SCHEAFFER AND WILLIAM MCK. SHEIPE, OF POTTSVILLE,
PENNSYLVANIA.

TAKE-UP.

Application filed March 14, 1925. Serial No. 15,485.

This invention relates to an improved device known in the art as a take-up, the same having particularly reference to a device of this class, which is especially designed for 5 use in connection with circular knitting machines.

The primary feature is the provision of the structure which is particularly, but not necessarily, designed for use upon a conventional knitting machine of the well-known Nye and Tredick type.

The invention embodies, among other inventions, two outstanding features, in that the structure is such as to render the operation 15 of the device substantially noiseless, and such as to permit the take-up rolls of the knitting machine to be removed or replaced with ease and facility.

Other features and advantages will, by 20 comparison, be brought out as the description goes on.

In the accompanying drawing, forming a part of this application, and in which like numerals are employed to designate like 25 parts throughout the same:

Figure 1 is an elevational view, partly in section, showing a device constructed in accordance with the present invention.

Figure 2 is an end elevation of the device, 30 as seen in Figure 1.

Figure 3 is a top plan view, with portions removed.

Figure 4 is an enlarged detail view of the readily releasable retaining means for the 35 take-up roll.

Referring to the drawing of this detail, it will be seen that the reference character 1 designates what may be described as a hanger, the same being provided, at its upper end, with a right angular portion, including a horizontal part 2 and vertical part 3, the last named part constituting a bushing, in which a shaft 4 is journaled for rotation. This shaft is provided, on its upper end with a gear 5, and on opposite sides of this gear, the part 3 is provided with oppositely extending notched lugs 6, for fastening the device to an appropriate support. Here, it might be pointed out that 45 the gear 5 is adapted to mesh with suitable driving means (not shown). On the lower end of the shaft 4 is a bevelled pinion 7, meshing with a relatively larger bevelled gear 8, on a second shaft 9. The hanger is provided with integral extensions 10, provid-

ing bearings for the shaft 9. Secured to the shaft 9 for rotation therewith is a pulley 11 and a spacing sleeve 12 is interposed between this pulley and the adjacent bearing 10. A suitably shaped gear casing 13 is 60 screwed or otherwise detachably fastened to the hanger, and houses the gears 7 and 8, to eliminate noise.

At its lower end and in one longitudinal side, the hanger 1 is provided with a substantially V-shaped recess 14, cooperating with a recessed block 15, in forming a sectional bearing for the reduced journal 16, carried by the take-up roll 17.

As is more clearly shown in Figure 4, the bearing block 15 is detachably mounted upon the web 18 of a pivoted latch 19. Also carried by this latch is a finger loop 20, which is adapted to be grasped, in swinging the latch to the position shown in Figure 4, to permit insertion of the journal 16. This latch is held in closed position, as shown in Figures 1 and 2, by means of a removable finger bolt 21 tapped into a socket formed in the hanger. It is yet to be pointed out that a relatively large pulley 22 is fastened to the journal 16, beneath the aforesaid pulley 11 and a friction drive belt 23 is trained over these pulleys.

It is obvious from the foregoing description that the device is appropriately mounted upon a relatively stationary support, and that the gear 5 is meshed with appropriate driving means and through the medium of the bevelled gearing and belt drive, the take-up roller, a part of the knitting machine is set into rotation and driven in the usual way. The important feature of the construction, as before stated, resides in the novel means employed for facilitating application and removal of the take-up roll 17.

In connection with this device, attention is also directed to the fact that in addition to being adaptable for ready application to a conventional type of circular rivet knitting machine, it possesses such features as these: First, it is practically noiseless, it does not jar or vibrate the machine, which jarring frequently causes the machine to accidentally cut holes in the work. Moreover, there is less wear and tear, which results in the reduction in the purchase of parts and renders the upkeep less expensive. Further, it serves to form better rolls, and produces an even and steady tension on the goods at 110

all times. Furthermore, there are no parts to get out of order, and this is an important advantage over the commonly marketed devices utilized for this purpose. Then, too, it can be installed in a very short time and requires no alteration of the existing parts of the machine, it being unnecessary, after the device is in place, to utilize a screw driver, or the like, in removing the rolls. 10 These and other advantages and features of the invention are doubtless made apparent by the foregoing description and drawing. For this reason, a more lengthy description is thought unnecessary. 15 Minor changes coming within the field of invention claimed may resorted to, if desired.

We claim:

1. In a take-up device of the class described, a recessed hanger, a pivoted latch carried by said hanger and disposed adjacent said recess, said latch being provided with a removable block adapted to fit into said recess forming a bearing for the journal 25 of a take-up roll, means for retaining said

latch in operative position, said hanger embodying an angular portion, shafts mounted upon said hanger, intermeshing gears carried by the shafts, and a gear housing carried by said hanger. 30

2. In a take up device of the class described, a hanger having an angular portion at its top and provided adjacent its lower end in one side with a substantially V-shaped recess, the bottom of which constitutes a portion of a bearing, a channel shaped latch pivotally mounted upon the hanger, a substantially V-shaped block carried by the bight portion of the latch and swingable into said recess, the apex portion of said block being notched to form the remaining portion of said bearing, means for retaining said latch closed, and operating means carried by the latch to permit it to be swung to open position. 35 40 45

In testimony whereof we affix our signatures.

CHARLES A. SCHEAFFER.
WILLIAM MCK. SHEIPE.
